UNITED STATES PATENT OFFICE

WILLIAM F. FERGUSON, OF CANDLER, NORTH CAROLINA

WINDOW FIXTURE

Application filed July 22, 1932. Serial No. 624,098.

This invention relates to the broad class of window fixtures and appliances and has more specific reference to a special selection and assembly of details forming a contrivance for supporting window shades, curtains, draperies and the like.

In accordance with the principle of the invention, I provide single and double type structures, that is, one type of the device for use in connection with ordinary single windows and a slightly modified type of device susceptible of practical usage in connection with duplex or double type windows.

Generically stated, novelty is predicated upon the use of special prong equipped attaching frames for detachable connection with the window frame, a spring for connecting the frames together in assembled relation and maintaining them in position, together with slideable adaptation units mounted on the frame and constructed to accommodate curtain and drapery supporting rods as well as conventional window shades.

Other structural features and advantages of the invention will become more readily apparent from the following description and drawings.

In the drawings:

Figure 1 is a front elevational view showing the style of invention used in connection with double types of windows.

Figure 2 is a similar view showing the single type device.

Figure 3 is a top plan view of the duplex spring anchoring fixture shown at the center in Figure 1.

Figure 4 is an elevational and sectional view of one of the end fixtures.

Figure 5 is a detail sectional view taken on the plane of the line 5-5 of Figure 2.

Figure 6 is a similar section on the line 6-6 of Figure 2.

Figure 7 is a detail perspective view of the duplex fixture hanger.

As a matter of simplicity, I first call attention to the single type device illustrated in Figure 2, in which figure the conventional window frame is designated by the numeral 8, the sash by the numeral 9. In this arrangement it will be observed that the as-

sembly forming the detachable frame engaging devices are the same in each instance.

In other words, each device comprises an elongated U-shaped wire frame 10 whose spaced parallel arms are distinguished by the numerals 11, said arms terminating in laterally directed end portions 12 which in turn are formed with pointed anchoring prongs 13.

At the opposite end the device is formed with a shank 14 which terminates in a hook 15 to which an eye 16 on the end of a coil spring 17 is attached. The spring is attached to both of the devices 10 in this manner as shown in Figure 2 so as to embed the prongs 13 in the ends of the window frame bar so as to hold the frames in position. The frames serve as retention devices for the slide units.

Each slide unit comprises a plate 18 having its edge portions formed with eyes 19 slideable on the arms 11. Formed integral with and projecting laterally from the plate at one end are adapter elements 20 and 21 to accommodate conventional rods and bars (not shown) such as are used at the present time for supporting curtains and draperies.

At its inner end the plate is formed with an apertured ear 22 to accommodate the adjacent pintle or journal (not shown) of a conventional window curtain. The numeral 23 designates a clamping plate held in place by a bolt 24 as shown in Figure 5 thereby holding the slide in different adjusted positions as conditions require.

The same fundamental principle of construction is carried forth in the double arrangement shown in Figure 1 and the same reference characters are employed to designate the same parts. The only difference here is that the numeral 10a designates a double acting wire frame which has a hook at opposite ends and which carries a pair of slides. This is supported in place by a hanger 25 which is formed from wire and provided with a suspension hook 26 and pointed attaching prongs 27 as shown in Figure 7.

I might also mention that the sliding plates may if desired, be provided with triangular

spurs 28 to bear against the frame to aid in stabilizing and maintaining the parts in proper relative positions.

In both embodiments of the invention it is evident that I provide a pair of attaching frames of general U-shaped form, these being arranged at longitudinally spaced points and having hooks or prongs at their outer ends to become embedded in the ends of the window frames. Moreover, these wire frames have extended shanks at their inner ends terminating in hooks to accommodate eyes on the opposite ends of the coiled retention spring 15. This provides a simple structure where-
10 by the frames are held securely in place and allowed to be shifted up and down to the proper elevation. The wire frames thus made provide ideal mountings for the slide-
15 able plate units, which units are properly clamped in place and provided with appropriate accessories to accommodate both curtains, shades, draperies and the like.

It is submitted therefore that a structure of the type herein illustrated and described
20 constitutes a novel and desirable contribution to the trade and the art which is readily distinguishable and recognizable and forms an appreciable structural arrangement.

As a matter of further distinction, I call
30 attention to the fact that the numeral 10 in all figures designates the single type spring anchoring frame and the numeral 10a the duplex type. Fundamentally however, these are substantially the same in structural detail.
35 It is thought from the foregoing description that the advantages and novel features of the invention will be readily apparent.

It is to be understood that changes may be made in the construction and in the combination and arrangement of the several parts provided that such changes fall within the scope of the appended claim.

I claim:

A window fixture construction of the class
45 described comprising, in combination, a pair of duplicate anchoring devices, each device being in the form of a wire frame of general U-shaped form including spaced parallel arms terminating at their free ends in laterally directed anchoring prongs, the bight portion of said frame being formed into a shank terminating in a spring retaining hook, a coiled spring having eyes at its opposite ends detachably connected with the adjacent
50 hooks, a slide for each frame, each slide comprising a plate formed with integral portions slidably embracing the arms of the frame, and laterally directed adaptation elements to accommodate curtain hangers, window shades
55 and the like, a clamping clip carried by each plate, a retaining bolt for said clip, said clip being engageable with the arms of the frame to hold the slide in an adjusted position.

In testimony whereof I affix my signature.
